UNITED STATES PATENT OFFICE.

THOMAS JEFFERSON LEAGUE, OF CHICAGO, ILLINOIS.

DESIGN FOR A LAMP BASE.

Application filed December 3, 1925. Serial No. 15,629. Term of patent 3½ years.

To all whom it may concern:

Be it known that I, THOMAS JEFFERSON LEAGUE, a citizen of the United States, residing at Chicago, in the county of Cook and State of Illinois, have invented a new, original, and ornamental Design for Lamp Bases, of which the following is a specification, reference being had to the accompanying drawing, forming part thereof.

Fig. 1 is a plan of the outline of the base with a portion of the ornamentation completed, the unfinished portion within the marginal border being identical with the finished portion.

Figure 2 is a side elevation.

I claim:

The ornamental design for a lamp base, as shown.

In testimony whereof I affix my signature at 10 South La Salle Street, Otis Building, Chicago, Illinois.

THOMAS JEFFERSON LEAGUE.
